LEONIDAS L. COLEMAN, OF NASHVILLE, TENNESSEE.

Design No. 3,265, dated December 1, 1868.

DESIGN FOR A TRADE-MARK.

The Schedule referred to in these Letters Patent and making part of the same.

To all whom it may concern:

Be it known that I, LEONIDAS L. COLEMAN, of the city of Nashville, county of Davidson, and State of Tennessee, have originated and designed a new Impression or Picture, to be placed on or attached to an article manufactured by myself, to serve as a label or trade-mark, to prevent others from counterfeiting the same; and the following is a full, clear, and exact description thereof, reference being had to the accompanying drawings, making part of this specification.

Figure 1 is a view of the picture or trade-mark, showing its original features.

A is the nut or fruit represented on the picture, and composed of the colors, as shown thereon.

B are the leaves of the same.

C are the stems or twigs to which the fruit or nut is attached.

D is the background of the picture.

E is the lettering of the same.

F and F' are the borders, and represented by the different colors.

H is the background on which the word "Cure" is written.

Therefore, what I claim as my invention or design, and desire to secure by Letters Patent, is—

The design or picture, representing the nut or fruit A, with its leaves B and stems or twigs C, in combination with the lettering E and the borders F and the background D, when executed in such manner as to represent a fac-simile of the original herein set forth.

LEONIDAS L. COLEMAN.
